CANE OR UMBRELLA HANDLE.

No. 20,144.

Patented Sept. 9, 1890.

UNITED STATES PATENT OFFICE.

ALBERT ROSENSTEIN, OF LANCASTER, PENNSYLVANIA.

DESIGN FOR A CANE OR UMBRELLA HANDLE.

SPECIFICATION forming part of Design No. 20,144, dated September 9, 1890.

Application filed July 31, 1890. Serial No. 360,571. Term of patent 3½ years.

To all whom it may concern:

Be it known that I, ALBERT ROSENSTEIN, of Lancaster, in the county of Lancaster and State of Pennsylvania, have invented certain new and useful Improvements in Designs for Cane, Umbrella, or Parasol Handles; and I do hereby declare the following to be a full, clear, and exact description of the invention, such as will enable others skilled in the art to 5 make and use it, reference being had to the accompanying drawing, which forms part of this specification.

My invention relates to an improvement in designs for cane, umbrella, or parasol handles; and it consists in the novel shape and configuration of parts, whereby a pleasing and beautiful effect is produced, as will be more fully described hereinafter.

The accompanying photographic illustration represents my invention.

A represents the main portion of the handle, which is given practically an L shape, and which has preferably a suitable bead, rib, or flange I formed upon its side, and which rib or flange follows the general outline of the 25 handle. Climbing upon this handle is a monster or animal B, which is provided with two necks C, the two heads D, two sets of claws G, and two tails H, which are wound around the handle in opposite directions, as shown. The 30 two heads and necks of the animal are placed upon opposites of the horizontal portion of the handle, as shown.

A handle constructed as here shown presents a very attractive and handsome appearance and adds to the ornamentation of the article to which the handle is applied.

Having thus described my invention, I claim—

A design for a cane, parasol, or umbrella 40 handle, substantially as herein shown and described.

In testimony whereof I affix my signature in presence of two witnesses.

ALBERT ROSENSTEIN.
